TABLE

William Joseph Carr, Gardner, Mass., assignor to Heywood-Wakefield Company, Gardner, Mass., a corporation of Massachusetts

Filed Mar. 25, 1964, Ser. No. 79,168

Term of patent 14 years

(Cl. D33—14)

The figure is a perspective view of a table showing my design.

The faces of the pedestal members not shown are the same in appearance as the faces shown.

I claim:

The ornamental design for a table, as shown and described.
